SOUND REPRODUCING SYSTEM

Harry L. Forster, Buffalo, N. Y., assignor to
Colonial Radio Corporation, Buffalo, N. Y.

Application May 9, 1941, Serial No. 392,694

8 Claims. (CL. 179—1)

This invention relates to electrical sound reproducing systems involving amplifiers and loud speakers and more particularly to such a system particularly adapted to be employed in radio receivers, electric phonographs, public address systems and the like.

It is well known that most loud speakers of the so-called direct acting type, embodying no horn, have an undesired resonance peak. This peak is ordinarily located within the range of audio frequencies desired to be reproduced and in most cases falls near the low frequency end of the band. For example, a typical baffle loaded cone loud speaker such as is ordinarily employed in home radio receivers has a pronounced resonance peak in the neighborhood of 200 cycles. Such a resonance peak is undesirable under most circumstances because it tends to unduly increase the sound output in the neighborhood of the resonant frequency, thereby upsetting the desired tonal balance over the audio range.

Such a resonance peak is sometimes relied upon to increase the low frequency response of the speaker and particularly where the design of the speaker is such that if such peak were not present the low frequency response would be less than desired, but even in such cases the increase in response obtained by resonance appears only over a relatively small band of frequencies and the response of the speaker at frequencies below the resonance peak is usually very poor.

It is an object of this invention to provide a sound reproducing system by which the low frequency response of the system may be considerably increased both in magnitude and in range of frequencies.

It is a further object of this invention to provide such a sound reproducing system in which the amplification may be adjusted to compensate for the low frequency resonance peak usually present in the speaker, whereby the output of the system may be made more nearly uniform in spite of the resonance effect.

It is still a further object of my invention to provide an audio amplifying system which will have positive regeneration of a portion of the audio spectrum, usually the lower portion, zero regeneration another portion, usually higher, and negative regeneration over another portion, usually still higher.

It is still a further object of this invention to provide a system of the class described in which zero regeneration is supplied at the resonance peak of the loud speaker, positive regeneration for frequencies below the resonance peak and

negative regeneration for frequencies above the resonance peak.

It is still a further object of my invention to provide such a system which operates automatically, that is to say, one in which the apparatus inherently provides such an operation without attention or adjustment on the part of the operator.

Still other objects and advantages of my invention will be apparent from the specification.

10 In this application I have particularly pointed out and distinctly claimed the part, improvement or combination which I claim as my invention or discovery, and I have explained the principles thereof and the best mode in which I have contemplated applying those principles so as to distinguish my invention from other inventions.

In the drawing:

15 Fig. 1 is a circuit diagram of a system in accordance with my invention;

20 Fig. 2 is an equivalent network diagram useful in understanding the operation of my invention, and

25 Fig. 3 is a vector diagram illustrating the voltage and current relationships for one particular frequency.

30 Referring now more particularly to Fig. 1, in practicing my invention I prefer to employ an audio frequency amplifier of the so-called resistance coupled type. This amplifier may employ the first amplifier tube 1 having a cathode 1a, a grid or control electrode 1b and an anode or plate 1c. Audio frequency voltages may be impressed between the cathode 1a and control electrode 1b from any suitable output such as the detector of a radio receiver, a phonograph pick-up, a microphone or the like. The anode 1c may be connected through a resistance 2 to a suitable source of potential indicated as +B.

35 Coupling condenser C₁ may be connected to the top of resistance 2 and to control electrode or grid 3b of the second amplifier tube 3 which may have cathode 3a and plate or anode 3c. The control electrode 3b may be connected through resistance R₁ to ground. The primary winding 4a of a suitable output transformer may be connected on the one end to the anode 3c and on the other end to a suitable source of potential indicated as +B. Associated with the coil 4a

40 50 may be the core 4c and the secondary winding 4b one end of which may be connected to ground. The secondary winding may feed the voice coil 5a of loud speaker 5.

45 55 For the purposes of this discussion, it may be assumed that the loud speaker 5 is a conventional

loud speaker of the so-called dynamic type in which the voice coil moves axially in an annular magnetic field excited by either an electro-magnetic or a permanent magnet and drives a cone diaphragm.

The ungrounded terminal of secondary winding 4b may be connected through condenser C₂ and resistance R₃ in series to the grid 1b of the tube 1. In making this connection, care should be taken to obtain proper phasing. If reverse connections are made, pronounced oscillations are likely to occur. The grid 1b may be connected to ground through resistance R₄ and the resistances R₃ and R₄ together may be designated as R₂.

By proper choice of the values of resistances R₁ and R₂ and condensers C₁ and C₂, the circuit may be made to have positive regeneration at the low frequency end of the audio band, zero regeneration at a frequency above the frequencies of positive regeneration, and negative regeneration for all frequencies above the frequency of zero regeneration. By proper selection of these values the cross-over frequency (the frequency of zero regeneration) may be placed at any point within the audio resistance band, but I prefer to place it at or near the undesired low frequency resonance peak of the speaker.

I have found that best results are obtained for a typical small receiver when C₁ has a value in the neighborhood of .005 microfarad, R₁ 250,000 ohms, C₂ 750 m. m. f. and R₂ 2 megohms. With such values, and using a speaker having an undesired resonance peak at 200 cycles, I am able to supply 8 decibels of positive regeneration at 90 cycles, 10 decibels of negative regeneration at 400 cycles, and zero regeneration at 200 cycles, thus giving a bass peak at 90 cycles, 18 decibels above the response at 400 cycles.

It will be understood that the values of C₁, C₂, R₁ and R₂ may be varied to some extent, but a certain relationship must obtain between them in order to produce the desired effect. R₁ will ordinarily not be less than 200,000 ohms nor greater than 1.5 megohms. C₁ is directly related to R₁ in value in that the reactance of C₁ should be equal to the resistance of R₁ at the frequency for which zero regeneration is desired. C₂ and R₂ are similarly related to the impedance of the grid circuit of the tube 1 which usually will not be less than that of the tube 3 and may be considerably greater.

R₂ may be made to fall within the range from .3 megohm to 10 megohms and correspondingly C₂ may vary from .009 microfarad to 15 micro-microfarads. In any case the ideal relation between C₁ and R₁ and C₂ and R₂ is that

$$\frac{1}{2\pi f C} = R$$

were f is the frequency for which zero regeneration is desired. A certain latitude is permissible in that the reactance of the condenser may be made as small as 0.4 R or as large as 1.6 R, but ordinarily it will not be desirable to exceed these limits.

It is my belief that the explanation for the operation of the circuit is to be found in the variation in phase relations which occur in the two resistance capacity networks, the first being C₂-R₂ coupling the output of the amplifier as a whole back to the input, and the second being C₁-R₁ coupling the output of the first tube to the input of the second tube. These two networks are of the same pattern and if proper

values of capacity and resistance are assigned to them, become networks in which there is a phase shift of from something just over zero to something just under 90° depending upon the frequency of the signal passing through the network.

As an example of the behavior of such a network, consider the network shown in Fig. 2, in which the values are chosen so that

$$\frac{1}{2\pi f C} = R$$

at a frequency f. It can be shown that there are definite mathematical relationships between the voltages E and E₂ across terminals 1, 2 and 3, 4 respectively, E₁, the voltage across condenser C, and I, the current in the network.

Considering terminals 3 and 4 to be open and the voltage E applied between terminals 1 and 2, it will be seen that the current I in the circuit flows through terminal 1, condenser C, resistance R and terminal 2 in that order during one-half of the cycle and in the reverse direction during the other half. Since a common current is flowing through C and R, and since the voltage across a condenser always lags the current through it by approximately 90°, and the voltage across a resistance is always in phase with the current through it, it follows that the voltages across condenser C and resistance R are 90° out of phase, the voltage across condenser C lagging the voltage across resistance R. Since by assumption the reactance of condenser C is equal to the resistance R at the frequency f, the voltage drops across them are equal in magnitude.

The voltage relationships for any particular frequency, for example frequency f, at which the reactance of condenser C equals the resistance R, may be plotted and this has been done in Fig. 3. E is the input voltage. It is clear that the load current leads the impressed voltage by 45° so I may be laid off 45° ahead of E. Since E₂ is in phase with I, E₂ is laid off on the same vector as I and since E₁ lags I by 90°, it may be laid off as shown.

Having established the fact that E₂ leads E by 45° when the reactance of condenser C equals resistance R for a frequency f, we now assume another frequency, 2f. For the frequency 2f the voltage drop across C is one-half of that across R, since the reactance of condenser C is equal to one-half R at the frequency 2f, and the phase angle between the current and voltage is

$$\tan^{-1} \frac{X_2}{R}$$

or about 27°, and E₂ leads E by 27°.

At a third frequency

$$\frac{f}{2}$$

the magnitude of X₂ is 2R and similarly the phase angle about 64°. Arranging these in the form of a table, we have the following:

Frequency	Magnitude of X ₂	Angle by which E ₂ leads E	Degrees
2f	1/2 R	27	45
f/2	2R	64	90

Since we have in the present instance two such networks in series in the circuit, the amount of phase shift will be double that shown in the

table for any particular frequency and again tabulating we have the following:

Frequency	Angle by which E_2 leads E
	Degrees
$2f$	52
$f/2$	90
	128

From this it will be seen that for frequencies above f , the crossover frequency, the feedback voltage is negative or degenerative, whereas at frequencies below f the feedback voltage will become positive or regenerative rather than degenerative.

While I believe the foregoing explanation to be correct, I do not wish to be bound thereto. Whatever the explanation, the circuit operates as described and produces the results above noted, as proved by repeated tests.

It will be noted that the division of R_2 into two components R_3 and R_4 forms a voltage divider limiting the amount of feedback. Variation of the relative values of R_3 and R_4 may control the amount of feedback, but so long as R_2 is not charged in relation to C_2 the crossover frequency will remain substantially constant.

While I have shown and described certain preferred embodiments of my invention, it will be understood that modifications and changes may be made without departing from the spirit and scope of my invention.

I claim:

1. In an audio frequency amplifier, in combination, a first amplifier tube, a second amplifier tube, a non-resonant resistance-capacity network coupling the plate circuit of the first tube to the grid circuit of the second tube, and a resistance capacity network coupling the output circuit of said second tube to the grid circuit of the first tube, the values of resistance and capacity in said networks being such that the reactance of the capacity in each network is equal to the resistance in said network at a frequency within the audible range.

2. In an audio frequency amplifier, in combination, a first amplifier tube, a second amplifier tube, a non-resonant resistance-capacity network coupling the plate circuit of the first tube to the grid circuit of the second tube, and a resistance capacity network coupling the output circuit of said second tube to the grid circuit of the first tube, the values of resistance and capacity in said networks being such that the reactance of the capacity in each network is equal to the resistance in said network at a frequency within the audible range, and adjacent the low frequency end thereof.

3. In an audio frequency amplifier, in combination, a first amplifier tube, a second amplifier tube, means for coupling said tubes in cascade, a non-resonant reaction coupling from the output circuit of said second amplifier tube to the input circuit of the first amplifier tube, the constants of said couplings being so chosen that the phase relations of energy fed back are such as to provide positive regeneration over part of the audible range, and negative regeneration at frequencies above said part of the audible range.

4. The combination with a loud speaker having undesired resonance near the low-frequency end of the audio band, of an amplifier for feeding

said speaker comprising a pair of tubes in cascade, a non-resonant resistance-capacity network coupling the plate circuit of the first tube to the grid circuit of the second tube, a resistance-capacity network coupling the output circuit of said second tube to the input circuit of the first tube, an audio circuit coupling the output circuit of said second tube and said loud speaker, the values of said resistance-capacity network being so chosen that said amplifier has positive regeneration below the loud-speaker undesired resonant frequency, and negative above said frequency.

5. The combination with a loud speaker having undesired resonance near the low-frequency end of the audio band, of an amplifier for feeding said speaker comprising a pair of amplifier tubes in cascade, a non-resonant resistance-capacity network coupling the plate circuit of the first tube to the grid circuit of the second tube, a resistance-capacity network coupling the output circuit of said second tube to the input circuit of the first tube, an audio circuit coupling the output circuit of said second tube and said loud speaker, the values of the resistance and capacity in said networks being so chosen that the reactance of the capacity in each network is equal to the resistance of the network at the undesired resonant frequency of the loud speaker.

6. In an audio frequency amplifier, in combination, a first amplifier tube, a second amplifier tube, a non-resonant resistance-capacity network coupling the plate circuit of the first tube to the grid circuit of the second tube, and a resistance-capacity network coupling the output circuit of said second tube to the grid circuit of the first tube, the values of resistance and capacity in said networks being so related that the angle of phase shift introduced by each network is substantially equal.

7. In an audio frequency amplifier, in combination, a first amplifier tube, a second amplifier tube, a resistance-capacity network coupling the plate circuit of the first tube to the grid circuit of the second tube, and a non-resonant resistance-capacity network coupling the output circuit of the second tube to the input circuit of the first tube, the capacity of each network being related to the resistance thereof in the relation

$$C = \frac{1}{2\pi f(R \pm .6R)}$$

where R is the resistance of the network and f is the crossover frequency.

8. The combination with a loud speaker having undesired resonance near the low frequency end of the audio band, of an amplifier for feeding said speaker comprising a pair of amplifier tubes in cascade, a non-resonant resistance-capacity network coupling the plate circuit of the first tube to the grid circuit of the second tube, a resistance-capacity network coupling the output circuit of said second tube to the input circuit of the first tube, an audio circuit coupling the output circuit of said second tube and said loud speaker, the capacity of each network being related to the resistance thereof in the relation

$$C = \frac{1}{2\pi f(R \pm .6R)}$$

where f is the undesired resonance frequency of said loud speaker.
